US00D746328S

(12) **United States Design Patent**
Kim

(10) **Patent No.:** **US D746,328 S**
(45) **Date of Patent:** **** Dec. 29, 2015**

(54) **DISPLAY SCREEN OR PORTION THEREOF
WITH ICON**

(71) Applicant: **Samsung Electronics Co., Ltd.,**
Suwon-si (KR)

(72) Inventor: **Jae-In Kim**, Goyang-si (KR)

(73) Assignee: **Samsung Electronics Co., Ltd.,**
Suwon-si (KR)

(**) Term: **14 Years**

(21) Appl. No.: **29/476,206**

(22) Filed: **Dec. 12, 2013**

(30) **Foreign Application Priority Data**

Sep. 3, 2013 (KR) 30-2013-0045227

(51) **LOC (10) Cl.** **14-04**

(52) **U.S. Cl.**

USPC **D14/489**

(58) **Field of Classification Search**

USPC D14/485, 488-493, 486
CPC G06F 3/04817; G06F 8/34; G06F 3/048

(57) **CLAIM**

The ornamental design for a display screen or portion thereof with icon, as shown and described.

DESCRIPTION

FIG. 1 is a front view of a display screen or portion thereof with icon, showing my new design;

FIG. 2 is a front view of a display screen or portion thereof with icon, showing an alternative embodiment of the new design;

FIG. 3 is a front view of a display screen or portion thereof with icon, showing an alternative embodiment of the new design; and,

FIG. 4 is a front view of a display screen or portion thereof with icon, showing an alternative embodiment of the new design.

The dot-dash broken lines illustrating portions of the display screen are included for the purpose of illustrating environmental structure and form no part of the claimed design.

1 Claim, 2 Drawing Sheets
